UNITED STATES PATENT OFFICE.

JOSEPH W. STOCKWELL AND RAYMOND COATES, OF JACKSON, MICHIGAN.

GARMENT-SUPPORTING DEVICE.

No. 801,619.

Specification of Letters Patent.

Patented Oct. 10, 1905.

Application filed December 15, 1904. Serial No. 237,047.

To all whom it may concern:

Be it known that we, JOSEPH W. STOCKWELL and RAYMOND COATES, citizens of the United States, and residents of Jackson, in the county 5 of Jackson and State of Michigan, have invented a new and Improved Garment-Supporting Device, of which the following is a full, clear, and exact description.

Our invention relates to a device designed 10 for use in supporting garments, and especially designed as a combination trousers-button and drawers-supporter, although it is to be understood that the usefulness of the device is not strictly limited thereto.

15 Numerous inventions in the line mentioned above have been made; but they are all open to certain objections. Many of them require special manipulation to apply them to a garment. Others are so arranged as to be easily 20 detached after being applied, and as a usual thing they are heavy, clumsy, and too expensive for general use.

It is the object of our invention to overcome these objections and at the same time to 25 produce a device of the character described which will efficiently serve its purposes, which may be easily attached and detached, but which will not become detached accidentally, and which will be simple in construction and 30 cheap to manufacture. These results we preferably accomplish by making a device having two reverse hooks for supporting the garments and one or more hooks for securing it to one of the garments, all made out of a single 35 piece of wire.

Reference is to be had to the accompanying drawings, forming a part of this specification, in which similar characters of reference indicate corresponding parts in all the figures.

40 Figure 1 is a perspective view showing one form of our invention as it appears when in use. Fig. 2 is a side elevation of the same, showing the garment to which it is attached in cross-section; and Figs. 3 and 4 are perspective views of other forms in which our invention may be embodied.

It will be observed that in all the forms shown the device is constructed of a single piece of wire, and this is responsible for a 45 part of the simplicity and cheapness of the article; but it is to be understood that it could be constructed in other ways and still embody the chief features of the invention.

The forms of the invention illustrated comprising a hook *a*, preferably formed by bending the wire together at the center and giving

it a curve, so as to produce two nearly-vertical portions, as shown. This will result in a main body portion *b*, composed of the two parallel strands of wire which extend from the bottom 60 of the hook. This portion is bent over to the rear, forming a top portion *c*, and is again bent back, so as to form a second reverse or inverted hook *d*. The hooks *a* and *d* are therefore located on opposite sides of the body portion. 65 It will be observed that in the three forms shown this hook assumes different proportions and shapes, on account of the wire being bent in different ways before it is taken back toward the point *c*; but in all it is bent 70 downwardly on both sides to form resilient bars *m*, substantially parallel with the main body portion. These bars are provided with upwardly and inwardly inclined ends *n*, constituting hooks for entering the garment and 75 preventing its being lifted therefrom.

In the form shown in Figs. 1 and 2 the main body of the two parallel wires is bent downwardly at the point *c*, then inwardly to form the hook *d* and outwardly to form a 80 pair of bars *f* parallel with the portion *c* and preferably in the same plane therewith. This brings the wire up to a loop *g* near the portion *c*.

In the form shown in Fig. 3 the parts *e* 85 and *f* are substantially parallel with each other, but not in the same plane, the bars *f* being mounted upon the rear surfaces of the parts *e*, so as to make a more compact device. As the parts *f* ascend beyond the portion *g*, 90 they are preferably provided with loops *h*, which give additional resiliency, and if they extend above the top may be used to move the hook *d* away from the bars *m* to permit the garment to be easily inserted. 95

In the form shown in Fig. 4 the parts *e* and *f* are substantially the same as those shown in Figs. 1 and 2; but in the loop *d* an additional coil *k* is provided, which adds to the resiliency of the device in a manner well understood. From 100 the point *g* the wires extend in parallel relation with each other, so as to constitute the bars *m*, which are located in parallel relation with the main body *b*, and at a distance therefrom.

105 It will be understood that from the extreme end of the tongue of the loop *a* to the hooks *n* the wires of which the device is composed are always parallel to each other and during most of their course are in contact with each other, especially in the form shown in Fig. 3. The bars *m*, however, in all the forms are sepa-

rated from each other a distance about equal to the width of two wires of the main body *b*. This provides for the securing of the hooks *n* into the garment at a distance from each other sufficient to enable them to securely hold the device. If they were in contact with each other, they would have hardly more effect than a single hook, and while a single hook would secure the device under ordinary circumstances and while we reserve the right to employ such a construction we prefer to employ the two hooks separated from each other and both exterior to the main body of the wire on the other side of the garment. It will be understood that the hooks *n* could also be spread farther apart, so as to provide a greater surface for the fastening of the device to the garment, and that the separation of the hooks from each other prevents the swinging of the device about any point as a center and also reduces the danger of tearing the garment. It will be seen that it is necessary for the bars *m* to have a certain amount of resiliency with respect to the body *b* in order to permit the bars to be bent back far enough to allow for the insertion of the garment. This is secured in all of the modifications illustrated, and the loops *h* and *k* afford increased resiliency over that provided for in the other forms illustrated.

In the use of the device the bars *m* are drawn back from the body *b* sufficiently to permit the insertion of a garment—as, for example, the waistband of a pair of trousers—between the ends of the hook *n* and the body *b*. The device is then slid downwardly to the position shown in Figs. 1 and 2, and upon the release of the bars *m* it will be readily understood that the hooks *n* will engage in the garment and securely hold the device in position against any lifting tendency on the garment or any weight of the garment. Furthermore, the application of any weight to the hook *a*, as by the engagement thereof with a strap on the drawers, will not result in the sliding of the device downwardly upon the trousers on account of the bent portion *c*, which is substantially horizontal and will engage with the top of the waistband.

While we have illustrated and described certain forms in which our invention may be embodied, it is to be understood that it is not strictly limited to these forms, but can be constructed in other ways in accordance with the scope of the claims.

Having thus described our invention, we claim as new and desire to secure by Letters Patent—

1. A garment-supporting device, comprising a main body portion, a hook projecting from one side thereof, an inverted hook on the opposite side of the body portion, adapted to suspend a garment, and means at the rear of the first-mentioned hook for rigidly securing the device to a garment or the like; said

means comprising a hook resiliently mounted with respect to the body portion.

2. A garment-supporting device, comprising a body portion, a resilient bar substantially parallel therewith and spaced therefrom, a hook on the bar projecting toward the body portion, a hook on the body portion on the side opposite the bar, and an inverted hook on the body portion.

3. An article of manufacture, comprising a body portion having a hook at its lower end and extending to one side thereof, a top portion extending from the body portion on the opposite side from the hook, a second hook in an inverted position extending downwardly from said top portion, a bar extending downwardly from the top of said inverted hook, means for resiliently connecting said bar with the top portion, and a hook on the lower end of said bar projecting upwardly and toward the body portion.

4. An article of manufacture, composed of a single piece of wire, a bend being formed at the center of said piece of wire, the two parts of the wire extending upwardly from the bend to form a body portion, then rearwardly from the upper end of the body portion, thence downwardly therefrom to form an inverted hook, and from the extremity of this hook upwardly again to the upper end of the body portion, thence downwardly upon a line parallel to the body portion but spaced therefrom, and each of the last-mentioned downwardly-extending portions of the wire being provided with means for securing it to a garment located at its lower end.

5. An article of manufacture, consisting of a single piece of wire, and comprising a hook formed at the center of said piece of wire, the wire being bent upon itself at the extremity of said hook, the two parts thereof extending parallel to each other upwardly from the hook to form a body portion, rearwardly from the upper end of the body portion, thence downwardly therefrom to form an inverted hook, and from the extremity of this hook upwardly again to the upper end of the body portion, then downwardly upon a line parallel to the body portion but spaced therefrom, and each of said portions of the wire being provided with a sharpened upwardly and inwardly inclined hook at the lower end of said last-mentioned downwardly-extending portion.

6. An article of manufacture, composed of a single piece of wire and comprising a bend formed at the center of said piece of wire, the two parts thereof extending upwardly from the bend to form a body portion, then rearwardly from the upper end of the body portion, thence downwardly therefrom to form an inverted hook, and from the extremity of this hook upwardly again to the upper end of the body portion, thence being bent in a reverse direction to form resilient loops above the upper end of the body portion, and then

downwardly along a line parallel to the body portion, and each end of the last-mentioned downwardly-extending portions of the wire being provided with means for securing it to

5 a garment.

7. An article of manufacture comprising a body having a hook on one side thereof, a portion extending from the body on the opposite side from the hook, a second hook in
10 a reverse position extending from said portion in a direction toward the end of the body upon which the first-mentioned hook is located, a bar extending from a point beyond

said portion in a direction parallel with the body toward the first-mentioned hook, means 15 for resiliently connecting the bar with said portion, and a hook on the end of said bar projecting at an angle toward the body.

In testimony whereof we have signed our names to this specification in the presence of 20 two subscribing witnesses.
